United States Patent Office

Des. 190,365
Patented May 23, 1961

190,365

RESTAURANT BUILDING

Frederic P. Merrels, 5609 Wilson Lane, Bethesda, Md.

Filed Feb. 2, 1959, Ser. No. 54,423

Term of patent 14 years

(Cl. D13—1)

Des. 190,365

PAGE 2

Fig. 1 is a side view in elevation of a restaurant building showing my new design;

Fig. 2 is a rear elevation thereof;

Fig. 3 is a front view of the building;

Fig. 4 is a top plan view;

Fig. 5 is an enlarged section on line 5—5 of Fig. 2;

Fig. 6 is a perspective view of the building.

I claim:

The ornamental design for a restaurant building, as shown.
